(No Model.)

G. H. WARREN.

Sulky Plow Attachment.

No. 240,290.

Patented April 19, 1881.

UNITED STATES PATENT OFFICE.

GEORGE H. WARREN, OF HAMPTON, IOWA.

SULKY-PLOW ATTACHMENT.

SPECIFICATION forming part of Letters Patent No. 240,290, dated April 19, 1881.

Application filed August 20, 1880. (No model.)

To all whom it may concern:

Be it known that I, GEORGE H. WARREN, of Hampton, in the county of Franklin, and in the State of Iowa, have invented certain new and useful Improvements in Sulky-Plow Attachments; and I do hereby declare that the following is a full, clear, and exact description thereof, reference being had to the accompanying drawings, and to the letters of reference marked thereon, making a part of this specification.

This invention relates to certain improvements in that class of sulky-plows in which the plow-beam is operated to elevate or depress the plow at pleasure, by means of a suitable foot-lever; and it is especially designed to be employed in connection with the invention for which Letters Patent of the United States No. 225,668 were granted to me the 16th day of March, 1880, although it is applicable to all other sulky-plows of a similar nature.

The object of the present invention is to provide a foot-lever for a sulky-plow that may be automatically locked and unlocked and shifted to any desired position by the action of the foot alone, to elevate or depress the plow-beam and plow, and, in connection with such foot-lever, to provide a foot-rest of simple construction, which will form a fulcrum-plate, which may be attached to any suitable portion of the frame of the plow by means of a single bolt, and which, in being thus secured, will hold the fulcrum-pin in its seat independent of other connections, as more fully hereininafter specified. These objects I attain by the devices illustrated in the accompanying drawings, in which—

Figure 1 represents a perspective view, showing my improved foot-rest and lever attached to a portion of the frame of the plow; and Fig. 2 a sectional view on the line $x-x$ of Fig. 1. Fig. 3 is a side elevation of a sulky-plow, showing my improved foot-lever and rest attached thereto.

The letter A indicates the foot-rest, consisting of a section of cast metal provided with downwardly-extending projections a at each end, having horizontal lips b , which are adapted to engage under the edge of the bail B or other

suitable supporting part of the frame of a plow. Midway between the ends of the said section, on the upper side, is formed a recess, C, from which extends horizontally a lip, D, which is provided with an aperture, E, for the bolt F, by means of which the device is secured to the plow, the said bolt extending through the frame at G. At each side of the recess, on the lower side of the section, are formed the short longitudinal recesses or sockets H, which constitute a seat for the fulcrum-pin I of the foot-lever K. The said foot-lever is constructed in the form of an angle-lever, with the fulcrum-pin at the angle, in such position that the portion of the lever at the angle will set in the recess C, so as to permit the lever to vibrate freely therein when the foot-rest is secured to the frame of the plow. The said angle-lever is provided with foot-pieces or pedals K' at its extremities, by which it may be conveniently operated by foot-power. To one extremity of said lever is secured loosely or pivoted the rod L, which is provided with a series of apertures, l, by means of which the lever may be adjustably connected to the plow-beam. The foot-piece or pedal, at the other extremity of the foot-lever, is slotted longitudinally, and has fulcrumed in it an angle-lever, M, one arm of which is adapted to fit in a recess in the face of the pedal, and form a bearing by which the said lever M may be operated by foot. The other end of said lever extends downward, so as to have a bearing upon the upper face of the lip D, whereby the foot-lever is locked in place when elevated.

The operation of my invention will be evident from the above description without further explanation.

Having thus described my invention, what I claim, and desire to secure by Letters Patent, is—

1. In combination with the foot-lever of a sulky-plow, the angle-lever M, pivoted in a slot in one arm, K, of the same, and provided with bearings at opposite ends, by which it may be operated to lock and unlock the said foot-lever, substantially as specified.

2. The combination, with the foot-rest A,

constructed with recesses C H, the foot-lever
K, pivoted therein, and having an angle-
clutching lever, d M, fulcrumed in a recess in
the upper arm thereof, the other arm being
5 connected with the forward end of a plow-
beam by a pitman, L, arranged and operating
as set forth.

In testimony that I claim the foregoing I
have hereunto set my hand this 24th day of
July, 1880.

GEORGE H. WARREN.
